US00D531121S

(12) **United States Design Patent** (10) **Patent No.:** **US D531,121 S**
Fort et al. (45) **Date of Patent:** **** Oct. 31, 2006**

(54) **PORTION OF A GROUND FAULT INTERRUPTER**

(75) Inventors: **Tucker H. Fort**, New York, NY (US); **Mark B. Greenwald**, Westport, CT (US); **Jean Claude Marcou**, Limoges (FR); **Jay J. Mendelson**, Hartsdale, NY (US); **Gunter A. Gallas**, Woodbury, NY (US); **Gregory Moreinis**, Forest Hills, NY (US); **Jeffrey J. Ausfeld**, New York, NY (US); **Yuliy Rushansky**, Port Washington, NY (US)

(73) Assignee: **Cooper Wiring Devices, Inc.**, Peachtree City, GA (US)

(**) Term: **14 Years**

(21) Appl. No.: **29/243,098**

(22) Filed: **Nov. 18, 2005**

Related U.S. Application Data

(63) Continuation of application No. 29/193,494, filed on Nov. 10, 2003, now Pat. No. Des. 512,021.

(51) **LOC (8) Cl.** **13-03**

(52) **U.S. Cl.** **D13/139.3**

CLAIM

The ornamental design for a portion of a ground fault interrupter, as shown and described.

DESCRIPTION

FIG. 1 is a front, bottom and right side perspective view of the design;

FIG. 2 is a front view thereof;

FIG. 3 is a right side view thereof; and,

FIG. 4 is a front, bottom and right side perspective view of the design in combination with a wall plate.

In all of the views, the dotted lines are for environmental purposes only and form no part of the claimed design. The rear is not part of the claimed design.
